G. O. MORTON.
DRYING FORM FOR HOSIERY.
APPLICATION FILED APR. 6, 1918.

1,323,642.

Patented Dec. 2, 1919.

UNITED STATES PATENT OFFICE.

GUST O. MORTON, OF ROCKFORD, ILLINOIS.

DRYING-FORM FOR HOSIERY.

1,323,642.

Specification of Letters Patent.

Patented Dec. 2, 1919.

Application filed April 6, 1918. Serial No. 227,005.

To all whom it may concern:

Be it known that I, GUST O. MORTON, a citizen of the United States, residing at Rockford, in the county of Winnebago and 5 State of Illinois, have invented certain new and useful Improvements in Drying-Forms for Hosiery, of which the following is a specification.

In the course of hosiery making, the 10 knitted article, whether a sock or stocking, is drawn in a dampened or wet condition onto a form to be dried. Heretofore, in knitting mills the common practice has been to employ imperforate hollow forms, into 15 which steam was supplied for drying the stocking by conduction through the agency of the heated form. This drying process, however, is slow; and the primary object of the present invention is to hasten the drying 20 of hosiery.

With this general object in mind, I have provided a hollow drying form, the effective 25 drying area of which is of very closely perforated construction, so that a heating medium, such as hot air, supplied to the interior of the form will not be dissipated or spent as in heating a heavy and imperforate form, but will be immediately and directly applied to the knitted article, thereby drying 30 the same most quickly and efficiently.

I have also aimed to provide a drying form of improved construction characterized 35 by perforate sheet metal sides coupled together at their marginal edges by a smooth and continuous head, which serves as a guiding and shaping edge and facilitates drawing of the stocking onto and removing it from the form.

A still further object of my invention is 40 to provide an improved drying form of the character described, which may be manufactured at a comparatively low cost and will serve the purposes desired in a most practical and effectual manner.

45 Referring to the drawings,—

Figure 1 is a side view of a stocking form embodying my improvements; and

Fig. 2 is an enlarged sectional view taken 50 on the line 2—2 of Fig. 1.

Before entering into a description of the 55 particular construction of my improvements, it might be mentioned that the latter contemplate the use of drying forms of any shape desired. That is, in this art it is common practice to shape the form to suit the particular knitted article. The form may,

therefore, be constructed for drying and shaping a sock, stocking, mitten or any other knitted article. In the present illustration of my improvements I have taken as an example, a form shaped to receive and dry a woman's fashioned stocking, it being manifest as just explained, that the invention is in no way limited to this particular shape of drying form.

It is desired to shape the form so that the knitted article in a dampened or wet condition according to the nature of the preceding processes, may be drawn onto the form and dried to the shape thereof. Since socks and stockings are thus dried in very large quantities in knitting mills and the operation of placing and adjusting the knitted article on the form and removing it therefrom is performed by hand, it will be plainly evident that the form must be so shaped and constructed as to allow the performance of these operations easily and quickly. The shape and character, therefore, of the exterior surfaces of the form and especially of the edges thereof are of considerable importance. The body of my improved drying form is constructed of relatively fine gage closely perforated sheet metal so as to offer the least resistance to the passage of a heating medium therethrough. As shown in the drawing, the body of the form consists of sides 4 and 5 cut to the requisite shape and formed so as to meet at their marginal edges 6 and to jointly constitute a hollow form as shown in Fig. 2. This form, it will be understood, is shaped at any cross-sectional point, substantially as shown in Fig. 2, that is, the marginal edges meet and the intermediate portion is bulged or shaped concavo-convex so as to provide a central conduit 7 and exterior surfaces 8 over which the knitted article is drawn taut. The perforations as shown in Fig. 1, are simply illustrative of the general idea, it being understood that the entire effective drying area of the form is very closely perforated and that the perforations might be graduated in size, with the larger perforations at the bottom of the form, to insure even drying, although in practical use it is found that with perforations of uniform size throughout the length of the form the drying is sufficiently even and equally rapid for all practical purposes.

Means is now provided for securing together the marginal edges of the sides of

the form, for reinforcing the same, for providing a rounded finished edge which facilitates drawing of the stocking onto and removing it from the form, and also provides 5 a pronounced and accurate shaping edge. This means consists of what might be termed a coupling bead, preferably in the form of an exteriorly rounded channel shaped sheet metal piece 9 embracing and clamped onto 10 the marginal edges of the sides 4 and 5 of the form as plainly shown in Fig 2. To insure a positive and substantial connection, the edges of the perforated sides are turned outwardly, providing a continuous flange or 15 shoulder behind which the ends of the coupling member are engaged and securely clamped. The coupling member 9, as noted in Fig. 1, extends entirely around the marginal edge of the form, thus providing a 20 continuous smooth rounded edge. This coupling clamps and secures the sides 4 and 5 together in a very simple and substantial manner and also reinforces the structure. The bead-like coupling also provides a continuous smooth and rounded guiding edge 25 which would be otherwise difficult to obtain if the closely perforated sheet metal sides of the form were joined together by any other means. The present construction, therefore, 30 not only possesses various advantages, but is exceedingly simple and capable of production at a comparatively low cost. Forms of this character are sometimes of sectional construction, that is, having interchangeable 35 leg and foot sections, so that they may be adapted to stockings of different sizes. My present improvements are equally well adapted to this style of drying form, although the general practice where stockings 40 are dried in large numbers is to provide permanent forms for various sizes and styles of socks or stockings.

When the heating medium, preferably hot

air, is delivered into the lower end of the form it will quickly emanate through the 45 various perforations throughout the form and thus be directly applied to the knitted article thereon. In this way the heating medium is not dissipated but is applied in a most direct and efficient manner to the 50 article and the drying is accomplished very quickly. In the practical use of my improvements, it is found that socks and stockings can be dried in about one-fourth the time required with the use of forms hereto- 55 fore employed.

It is believed that the foregoing conveys a clear understanding of my improvements and of the objects prefaced above, and it should be understood that while I have illus- 60 trated one working embodiment thereof, various changes might be made in the construction without departing from the spirit and scope of the invention as expressed in the appended claims.

I claim:

1. A drying and shaping form comprising a pair of perforated metal side members meeting along their marginal edges and providing a hollow form, the marginal edges 70 being flanged outwardly, and coupling means embracing said flanges for binding the sides together and providing a marginal guiding and shaping edge about the form.

2. A drying and shaping form of the character described consisting of side members of flat material shaped to jointly constitute a hollow form, and a combined shaping edge and coupling means formed of sheet material to embrace and clamp the marginal 80 edges of said side members and providing an exteriorly smooth guiding and shaping surface extending about substantially the entire marginal length of the form.

GUST O. MORTON.
